ELECTRICAL CONDENSER

Stanley S. Cramer, Haddon Heights, N. J., assignor to Radio Condenser Company, Camden, N. J.

Application May 9, 1934, Serial No. 724,688

23 Claims. (Cl. 175—41.5)

This invention relates to improvements in electrical condensers, particularly of the variable type, such as are used in tunable circuits of radio receiving sets.

5 Because of the present-day practice of making smaller radio receiving sets, smaller units, including tuning condensers, must be used in their construction. To reduce the size of the condenser and still have sufficient capacity for the tunable 10 circuits, the plates must be brought closer together, which means that greater care must be used in the assembly of the stator and rotor groups of plates, else the warping stresses brought about in the manufacturing processes will prevent 15 accurate centering of the stator and rotor plates, and more time must then be spent in getting these plates into accurate alignment.

Such small condensers have thus become precision instruments because the capacity settings 20 must be stable and the condensers must be capable of withstanding the strains and stresses applied to them without affecting the capacity settings, because present-day practice allows only a small tolerance in the variations of the capacity of one 25 condenser of a gang with respect to another. This tolerance is on the order of 1 to 1.5 mmfd. While it is customary at the present time to provide the outer plates of a condenser unit so that they may be flexed at different points to compensate for cer- 30 tain variations in the condensers, including the circuit with which they are connected, the design of the condenser must be one to give great rigidity.

It is one of the objects of my present invention to produce a condenser which is relatively small 35 and of light weight as compared with previous designs of the same capacity, but one which will stand the various abuses without drifting of the capacity. At the same time, it is a further object to provide a construction which can be carried 40 out at an even lower cost.

Another object of my invention is to provide a construction in which the parts are so arranged as to facilitate the accessibility so that the assembly operations may be quickly and carefully 45 performed.

In the last few years it has been customary, in order to get rigidity and therefore stable capacity, to use an all-metal frame for carrying condensers, the frame being made from a single piece 50 of metal, usually of steel, having shield plates between units either swedged or riveted in place between the various units of the gang; or, as an alternative, the end plates have been swedged or riveted in place between the side members of the 55 frame in the same manner as the shield plates.

This sort of construction has generally been referred to as the "bath tub" type of frame, but such a frame makes the "gang" condenser of considerable weight. To materially reduce this weight, I have discarded the shell or "bath tub" 5 type of frame entirely and have made a frame having two rigid metallic end plates, preferably of steel, held together by very rigid metallic rods constructed and arranged with the end plates to produce a frame structure having a torsional 10 strength much greater than the frames heretofore used. On certain tests which I have made, I have found that the frames to be hereinafter described will stand more than twice the torsional force than the "bath tub" type of frame 15 previously referred to, with a drifting capacity of the condenser of less than $\frac{1}{4}$ of the amount of drift in the condensers mounted in the previously described frame.

The advantages of my new construction will 20 appear from the specification which follows. In the drawings:

Figure 1 is a plan view of a three-gang condenser, only one unit being illustrated of one form of my invention.

Figure 2 is a right-hand end view of Figure 1 with the rotor turned ninety degrees.

Figure 3 is a section on the line 3—3 of Figure 1.

Figure 4 is a section on the line 4—4 of Figure 1.

Figure 5 is a view similar to Figure 1, but showing a modified form of mounting the stator element.

Figure 6 is a view on the line 6—6 of Figure 5.

Figure 7 is a side elevation of a further modified form of three-gang condenser showing the rotor turned at an angle of ninety degrees from its zero or full capacity position. In this form, as well as in Figures 1 and 5, no trimmer condenser is illustrated.

Figure 8 is a view of the right-hand end of the gang condenser shown in Figure 7.

Figure 9 is a view looking at one end of the bottom of one of the stator units of Figure 7, 45 showing a part of the end plate and one shield plate.

Figure 10 is a partial view on the line 10—10 of Figure 7.

Figure 11 is a partial view on the line 11—11 50 of Figure 7.

Figure 12 is a section on the line 12—12 of Figure 7.

Figure 13 is a side elevation of a three-gang condenser similar to that shown in Figure 7, but 55

showing certain modified details of mounting the stators and fastening the end plates in position.

Figure 14 is a view of the right-hand end of 5 Figure 13.

Figure 15 is a view looking at one end of the bottom of one of the stator units of Figure 13, showing a part of the end plate and one shield plate.

10 Figure 16 is a partial sectional view on the line 16—16 of Figure 13.

Figure 17 is a side elevation of a further form of three-gang condenser similar to that shown in Figures 7 and 13, but with certain modified 15 details.

Figure 18 is a view of the right-hand end of 20 Figure 17.

Figure 19 is a partial view on the line 19—19 25 of Figure 17.

20 Figure 20 is a side elevation of a three-gang condenser, only two of the stator units being illustrated to show certain modified details.

Figure 21 is a partial view looking at the right-hand end of Figure 20.

25 Figure 22 is a view looking at the bottom of one end of the stator units shown in Figure 20, showing details of mounting the stator in the frame.

Figure 23 is a side elevation of the frame of 30 a three-gang condenser showing further modified forms of the details thereof.

Figure 24 is a fragmentary view of the right-hand end of the frame shown in Figure 23.

35 Figure 25 is a side elevation of one end of a three-gang condenser, showing one of the condenser units and showing a form of trimmer which may be used.

Figure 26 is a fragmentary view of the right-hand end of the frame shown in Figure 25.

40 Figure 27 is a fragmentary end view of a further modified construction of the condenser frame.

Figure 28 is a view looking at the bottom of Figure 27.

45 Figure 29 is an end view, part in section and part in elevation, of a still further modified form of construction.

Figure 30 is a side view of the end of a condenser as constructed in Figure 29.

50 Figure 31 is a side view of one end of a modified form of frame structure.

Figure 32 is an end view of Figure 31.

Figure 33 is a side view similar to Figure 31 of a condenser frame, but of a modified form of fastening the bars to the end bearing plates.

55 Figure 34 is an end view of Figure 33.

Figure 35 is a side view, partly in section, of one end of a condenser showing a still further modified form of fastening the bars to the end plates.

60 Figure 36 is an end view of Figure 35.

Figure 37 is an end view of a still further modified form.

Figure 38 is a part side and part sectional view 65 of Figure 37.

Figure 39 is a part-sectional and part-elevational view of a further modification.

Figure 40 is a partial side view of one end of a condenser showing how the end plates may be 70 welded direct to the frame rods.

Referring now to the different views, 1 and 2 are metallic end plates, preferably of steel and of a thickness to give considerable rigidity. Each of the plates 1 and 2 is provided with two sets 75 of lugs, one set, 3, being provided so that the

condenser may be mounted in one angular position, while the other set, 4, is provided so that the condenser may be mounted in a reverse angular position as will be clear by reference to Figure 2. For holding the end plates 1 and 2 in operative position, I provide two similar rods 5 and 6, preferably of steel and of a size to rigidly hold the plates 1 and 2 in position. This is accomplished by providing the rods 5 and 6 at their extremities with annular grooves 7 to receive 10 the forked end 8 of the end plates 1 and 2.

The grooves 7 are of a width so the end plates 1 and 2 will be force-fitted therein, while the width of the notch between the forked ends 8 is somewhat smaller than the diameter of the 15 portion 9 at the base of the grooves 7. Furthermore, the depth of the grooves 7 is such as to provide a considerable radial bearing surface for the forked ends 8 of the plates 1 and 2. Thus, when the rods 5 and 6 are forced into position 20 in the end plates 1 and 2, the plates are securely gripped in position. The rods 5 and 6 have additional annular grooves 10 to receive the forked ends of shield plates 11, but the depth of these grooves 10 need not be as great as the depth of 25 the grooves 7, but preferably the shield plates are securely gripped by the rods when they are forced into the position shown.

The end plate 1 carries a ball bearing race 12 similar to that shown in my Patent 1,800,719, for 30 supporting one end of the rotor shaft 13, the opposite end of which is supported in a ball thrust bearing 14 supported by an adjusting screw 15 in the end plate 2. While I have indicated this type of bearing in the end plate 2, it is understood 35 that a bearing similar to that in the end plate 1 may be used.

The rotor plates 16 are carried on the shaft 13 in any satisfactory manner as by grooves within 40 which the plates 16 are staked or otherwise held. The stator group of plates 17 is suspended from the frame rods 5 and 6 by a saddle 18 having forked ears 19 which tightly fit into annular grooves 20 in the rods 5 and 6. The projecting edge 21 of the saddle 18 overlaps the edge of an 45 insulator 22 and is fastened thereto in any satisfactory manner as by rivets 23.

The opposite end of the insulator 22 is fastened 50 to a stator tie bar 24 through the medium of a hollow rivet 25 through which solder is caused 55 to flow into engagement with a portion 26 of the tie bar 24, as best illustrated in Figures 3 and 4. However, it is to be understood that before the soldering operation takes place, an assembly tool has been inserted between the stator and rotor 55 plates to properly space them an equal distance apart, all in the manner as described and claimed in Cramer application Serial No. 717,860, filed March 28, 1934.

After the soldering operation is completed, the 60 tool is removed, thereby leaving each of the stators assembled in the frame without any torsional strains thereon.

As shown in Figures 5 and 6, the stator 17 of 65 each unit condenser is fastened to the plain rods 5 and 6 in a somewhat different manner from that shown in the previous figures. When the stator plates 17 are attached to their tie bars 24, there being one on opposite sides of each stator, an insulator 27 is riveted between the tie bars 24 and the shouldered portion of the plates 17. To the free end of the insulator 27, is fastened, as by rivets 28, a metallic support member 29 preferably in the form of a small steel plate, the opposite end of which extends into a longitudinal 70 75

slot in one of the members 5 and 6, and is staked thereto at 30, thereby giving a suspension type of mounting for the stator somewhat different from that shown in Figure 1.

In Figures 7 to 12 inclusive, I have illustrated a modified form of condenser in which the end plates 1 and 2 are rectangular in shape but held together by the frame rods 5 and 6 in a manner similar to that already described, except that each of the rods 5 and 6 has a longitudinal groove 31 preferably extending throughout its length, and the material 32 of the end plates is preferably staked inwardly out of the plane of the end plate so as to absolutely prevent the rods 5 and 6 from turning. Furthermore, the insulators 33, one on each side of the stator, are positioned in the grooves 31, being staked in position therein as more clearly shown in Figure 11.

Each of the insulators 33 has a metallic bracket 34 fastened thereto in any satisfactory manner as by rivets 35. The bracket 34 has a pair of inwardly projecting arms 36, one on each side of the insulator, and each arm 36 has a lip 37 extending, one toward the other, as is clearly shown in Figure 9. These lips 37 act as means for assisting in soldering the stator tie bar 24 to the bracket 34. The manner of positioning the rotor plates and stator plates with a special fixture for carrying out the soldering operation is similar to that already explained with respect to Figure 1. The bracket 34 is provided with a terminal 38 for making electrical connection to the stator. Also, it may be noted that each insulator 33 may have a tapped hole 39 to receive an adjusting screw for adjusting a trimmer plate which may be added to each unit in a manner as will be later referred to on one of the other forms of condensers illustrated such, for example, as shown in Figure 25, wherein the trimmer plate 43 is fastened to the shield plate 11. It may be noted in Figure 8 that the end plates 1 and 2 may be provided with re-enforcing ribs 40 punched either outwardly or inwardly.

In Figures 13 to 16 inclusive, each of the insulators 33 is staked into grooves 31 in the rods as in the form shown in Figure 7, and the rods 5 and 6 are attached to the end plates 1 and 2 in the same manner as already described. However, each stator is suspended from its pair of insulators 33 in a somewhat different manner as is more clearly illustrated in Figures 15 and 16, wherein a pair of studs 41 with shoulders 42 have reduced ends which pass through the insulator 33 and also through a trimmer plate 43 for riveting the trimmer plate 43 securely to the insulator 33. The opposite ends of the studs 41 are soldered in a manner previously explained to the stator tie bar 24 as clearly indicated in Figure 15.

To provide a cooperative capacity element for the trimmer plates 43, a rectangular-shaped bar member 44 is positioned in slots in the bottom of the end bearing plates 1 and 2, being staked in position at 45 as indicated. The bar 44 has tapped holes 46 to receive adjusting screws which pass through clearance holes 47 in the trimmer plates 43. The screws and insulating bushings used in holes 47 and the trimmer plates are not shown in Figure 13, but their function is well understood. Each trimmer plate has an ear or lug 48 thrown outwardly therefrom for the purpose of making electrical connection to the stator.

In Figures 17, 18 and 19, the construction is very similar to that shown in Figures 13 to 16 inclusive, except the frame rods 5 and 6 are moved inwardly toward the shaft, notches 49

being provided in the end bearing plates to assist in the assembly of the parts. This means that the studs 50 for supporting the stator, while similar in shape to the studs 41, are shorter, thereby making the condenser of less width than 5 in the form shown in Figures 13 and 14. In addition, a somewhat different style of trimmer plate 51 is used, one of these trimmer plates being indicated in position in Figure 17, it having a similar connecting lug 48 as in Figure 13. The trimmer plate 51 is also provided with inturned fingers 52 for preventing an insulator not shown but used for separating the plate 51 from the bar 44, from turning.

In some cases where the condenser is mounted 15 in what might be termed an upside-down position, the fingers 52 act as supports for this trimmer insulator. Where no trimmer plate is used, a terminal plate 53 is provided, the same being riveted to the insulator by the end of the studs 20 50.

In Figure 20, the frame members 1 and 2 are held together in the same manner; that is, by the rods 5 and 6, as has been described, but the stator group of plates, only two of which are 25 shown, are fastened to an insulating bar 54 which extends from end to end of the condenser through the end bearing plates 1 and 2, as well as through the shield plates 11, being held in slots in the end plates by an auxiliary metal bar 55 which 30 is staked in position at 56. Thus the metallic bar 55 may act as an element for a trimmer plate condenser which may be used, but which is not shown, and at the same time, it adds a certain amount of stiffness to the whole frame of the condenser. 35

In this form, each of the stators is carried by a bracket 57 fastened to the bar insulator 54 in any satisfactory manner as by rivets 58, the stator being soldered to the projecting fingers 59 40 in the manner explained in Cramer application, Serial No. 717,860, heretofore referred to. It may be noted that the end plates 1 and 2 are provided with arms or brackets 60 for mounting the condenser. Similar brackets may be attached to 45 the end bearing plates in certain of the other forms that have been described.

In Figure 23, the rods 5 and 6 are fastened to the end plates 1 and 2 in a manner similar to that shown in Figures 18 and 20. A metallic bar 61, similar to the bar 55, is staked into position in slots in the end plates 1 and 2 and in the shield plates 11, but in this case the bar insulator 62 does not pass through the end plates 1 and 2 but is held therebetween to the metal bar 61 as 55 by rivets 63. The stator group of plates is held to the insulator 62 in the same manner as in Figure 20.

In Figures 25 and 26, bar insulators 64, similar to 54, are used, but these bars pass through 60 slots in the end plates 1 and 2 and are held in position as by staking at 65. The stator group of plates is held to the insulators 64 by brackets 66 which have inwardly projecting fingers somewhat similar to the fingers 59 to which the stator tie bars are soldered. The bracket 66 extends downwardly over the insulator so as to act as one element of a trimmer condenser, the other element being a metallic member 67 which may have a bent end folded over and fastened to the shield plate 11 as by rivet 68. An adjusting screw 69 and insulator 70, as shown in Figure 25, are used for adjusting the position of the trimmer plate 67, it being understood that a thin insulator, such as a piece of mica, is mounted between the trim- 75

mer plate 67 and the face of the bracket 66 which is provided with a lug 71 for making electrical connection thereto.

Instead of the method of holding the insulator 54 as shown in Figures 25 and 26, the end plates 1 and 2 may be slotted to the edge and the insulator 64 held in position by flanged collar 72 forced into a slot as indicated in Figures 27 and 28. To allow some spring at the point where 10 the flanged collar 72 is used, the end plates 1 and 2 may be slotted as at 73.

Of the various forms of condensers utilizing a frame having end plates held together by heavy binding rods, I prefer the construction shown in 15 Figures 17 to 19 inclusive, where the stator plates are suspended from the binding rods and an auxiliary metallic bar is utilized for an element of the trimmer condensers, as well as acting as a stiffening member for the frame.

20 In certain of the forms, for example in Figures 7, 13 and 17, the shaft 13 is indicated as being hollow and having a plurality of holes 74 therein. These holes are utilized for certain speed-producing mechanism which forms no part of my 25 present invention and will therefore not be further referred to herein.

In Figure 29, the end plates 1, only one of which is shown, are fastened together with rods 6 in about the same manner as has been previously described; likewise, the insulators 33 are held to the rod 6 by staking them in the grooves 30 in the rod 6. The insulator 33 has holes therein to receive one or more (2 being shown) insulating bushings 75. These insulators are preferably 35 of isolantite and may be held in the insulators 33 in any satisfactory manner as by a force-fit, the hole in the insulator 33 or the portion of the bushing 75 fitting in this hole being first treated with suitable cement.

40 The bushing 75 carries an eyelet 76, the outer ends of which are spun over at 77 to clamp a trimmer plate 78 securely in position. The free end of the trimmer plate 78 is arranged in overlapping relationship to an upstanding part 79 of the end plates 1, an insulator 80, preferably 45 of mica, being used as the dielectric between the parts 79 and the trimmer plate 78, the usual adjusting trimmer screw 69 and insulating bushing 70 being used. The stator tie bar 24 is provided with an outwardly extending lug 81 which 50 may be punched from the tie bar 24, or it may be made in a separate piece and soldered to the bent portion 26 of the tie bar 24 before the stator 17 is ready to be assembled in the condenser frame. In either case, after the stator has been 55 placed in the frame the extreme end 82 of the lug 81 is soldered across the outer face of the eyelet 76. By this construction, the soldering operation is brought to the extreme outside portion 60 of the condenser, thereby speeding up the operation of assembly, it being understood that the stator and rotor elements are positioned by a suitable fixture previous to soldering as heretofore referred to. In some cases, the insulation 65 pieces 33 may be dispensed with and a piece of steel used in their stead, the isolantite bushing 75 being sufficient to provide the necessary insulation in mounting the stator or stators to the frame.

70 In Figures 31 and 32 the metal of the end plate 1 is extruded or forced inwardly at 83 to provide a longer bearing for the rods 6, it being understood that the rods 6 have a force-fit into the end bearing plates 1 so that the frame produced is 75 a rigid one. I may also spot-weld the flange or

extruded portion 83 to the rod 6, as well as spot-weld the end of the rod to the plate around the line 84. In addition, the end plates may be provided with another rod 6 positioned at the bottom of the end plates, this extra rod being fastened to the plates in any of the ways described herein.

75 In Figure 33, the rod 6 has a reduced end portion at 86 force-fitted into the end plate 1, having an extruded portion 83 the same as in Figure 31, but in the opposite direction. The reduced end portion 86 may be also spot-welded around the distributed flange 83.

10 In Figure 35, the rod 6 has a reduced end portion 86 which is force-fitted into the end 15 plate 1. This reduced end may be knurled at 86 and the outer portion spun over the plate at 87.

15 In Figures 37 and 38, the end of the rod 6 may have some other form than circular, such as a 20 square shape 89, the outer end of the rod being spun over or welded at 89.

It is to be understood that any of the previously described forms may have a rod at the bottom of the end plates as shown in Figures 31 25 to 38 inclusive.

20 In Figure 39, the frame rods, only one of which, 6, is shown, are rectangular in shape. The frame rods are grooved to receive insulators 88 carrying the studs 41 which are soldered to the tie bars 30 at the point 26. Riveted on the outer ends of the studs 41, against the insulators 88, is a trimmer plate 78 which, however, in this case is formed upwardly into the desired shape and extends into capacity position with the frame rod 35 6, being adjusted with respect thereto by the screw 69, it being understood that the usual insulator is used between the trimmer plate 78 and the rod 6.

25 In Figure 40, the frame rod 6 is shown as being 40 welded to the end plate 2. The welding operation may be any of the well-known processes, such as spot, butt, or even arc welding, either of which will securely anchor the bars and end plates together, without being obliged to notch or perforate the end plates to receive the ends 45 of the frame rods. Therefore, when I speak of the end plates being securely anchored to the frame rods, this may be accomplished by any of the ways herein described which are broadly referred to as cooperative formations.

30 From what has been said, it will be understood 50 that the general object is to get, for a single unit or gang condenser, a frame that is light yet rigid, and one that is easy to make, and at the same 55 time provide a frame that will enable the condenser elements to be mounted thereon as free from stresses as possible.

What I claim is:

35 1. An electrical condenser comprising at least 60 one stator and rotor set of elements; a lightweight, high rigidity, non-warping frame for supporting said elements in close cooperative predetermined and non-drifting relationship, including rigid metal end bearing plates for supporting a shaft carrying the rotor plates, means 65 for securely holding said bearing plates in non-warping operative position including a plurality of metallic rods of a material and size as defined herein and disposed at least one on each side of the shaft, said rods at their extremities and the 70 end plates having cooperative formations force-fitted together in gripping engagement across a portion of the rods reduced in diameter as well as on opposite sides of said end plates adjacent said reduced rod portions, which latter engage- 75

ments comprise gripping surfaces of relatively large lateral area for the purposes described.

2. An electrical condenser as set forth in claim 1, further characterized in that a plurality of groups of stator and rotor elements are provided to form a gang condenser, at least two of said rods having additional grooves spaced between said groups of elements, and shield plates tightly fitting in said grooves similarly to said end plates.

10 3. An electrical condenser as set forth in claim 1, further characterized in that said rods have longitudinal grooves at least at each end, and parts of said bearing plates being forced into said longitudinal grooves.

15 4. An electrical condenser as set forth in claim 1, further characterized in that at least two of said rods have longitudinal grooves extending for at least the major portion of the length thereof, insulators fastened in the grooves of said rods 20 and extending away from the rods and having means attached to their opposite ends for supporting the stator element.

5. An electrical condenser as set forth in claim 1, further characterized in that at least two of said rods have longitudinal grooves extending from end to end of the rods, parts of said end plates being forced into said grooves, insulators staked in position in said grooves and extending 25 away from the rods, and means carried by the 30 insulators for attaching a stator element thereto.

6. A condenser as set forth in claim 1, characterized in that the stator having tie bars is suspended from at least two of said rods by means including insulators fastened to the rods and 35 studs having ends fastened to the insulators and their opposite ends being soldered to the tie bars.

7. A condenser as set forth in claim 1, characterized in that the stator having tie bars is suspended from at least two of said rods by means 40 including insulators fastened to the rods and studs having collars fitting against one face of the insulator, and ends extending from the collars and riveted over on the opposite side of the insulator, the opposite ends of the studs being 45 soldered to the stator tie bars.

8. A condenser as set forth in claim 1, characterized in that the stator having tie bars is suspended from at least two of said rods by means including insulators fastened to the rods and 50 studs having collars fitting against one face of the insulator, and ends extending from the collars and riveted over on the opposite side of the insulator, the opposite ends of the studs being soldered to the stator tie bars, and a trimmer condenser 55 plate also riveted to at least one of the insulators by the same stud ends.

9. A condenser as set forth in claim 1, characterized in that the stator having tie bars is suspended from a plurality of said rods by means 60 including insulators fastened to the rods and studs having collars fitting against one face of the insulator, and ends extending from the collars and riveted over on the opposite side of the insulator, the opposite ends of the studs being 65 soldered to the stator tie bars, and a trimmer condenser plate also riveted to at least one of the insulators by the same stud ends, said condenser being further characterized in that metallic bars extend between and are fastened to the end bearing plates, one on each side of the condenser, the 70 bars being positioned to act as one element of the trimmer condenser and as a frame-bracing member.

10. A condenser as set forth in claim 1, characterized in that the stator having tie bars is

suspended from a plurality of said rods by means including insulators fastened to the rods and parts carried by the insulators soldered to the tie bars of the stator, said parts comprising a metal plate fastened to each insulator, each 5 plate having arms extending beyond the sides of its insulator toward the stator, each arm having a lip extending one toward the other and being soldered to the stator tie bar on each side of the condenser.

10 11. A condenser as set forth in claim 1, characterized in that the stator having tie bars is suspended from a plurality of said rods by means including insulators fastened to the rods and parts carried by the insulators soldered to the tie bars of the stator, said parts comprising a metal plate fastened to each insulator, each plate 15 having arms extending beyond the sides of its insulator toward the stator, each arm having a lip extending one toward the other and being 20 soldered to the stator tie bar on each side of the condenser, said metal plate also acting as one element of a trimmer condenser.

12. For an electrical gang condenser having a plurality of stator and rotor groups of plates, 25 a light-weight, high-rigidity, non-warping frame including two rigid, metallic end bearing plates for the shaft carrying the rotors, said shaft and 30 stators being held in fixed non-warping spaced relationship by a plurality of metal rods of a material and size as defined herein and disposed 35 at least one on each side of the frame, said rods at their extremities and the end plates having cooperative formations press-fitted together in 40 the rods reduced in diameter as well as on opposite sides of said end plates adjacent said reduced rod portions, which latter engagements comprise annular gripping surfaces bounded by the outside diameter of the rods.

40 13. A frame for an electrical condenser as set forth in claim 12 further characterized in that the frame has rigid, metallic bar members located adjacent said rods on each side of the frame and extending between and rigidly fastened to said end bearing plates.

45 14. A frame for an electrical condenser as set forth in claim 12 further characterized in that the frame has bar members located adjacent said rods on each side of the frame and extending between and rigidly fastened to said end bearing plates, said bar members including strips of rigid 50 metal and insulation, the insulation strip carrying the stator plates.

55 15. A frame for an electrical condenser as set forth in claim 12 further characterized in that the frame has rigid, metallic bar members located adjacent said rods on each side of the frame and extending between and rigidly fastened to said end bearing plates, said bar members carrying 60 insulation strips that support the stator plates.

65 16. A frame for an electrical condenser as set forth in claim 12 further characterized in that the frame has bar members located adjacent said rods and extending between and fastened to said end bearing plates, said bar members including strips of metal and insulation, the insulation strip carrying the stator plates, said insulation strip being held in slots in the end bearing plates 70 by the metal strip.

75 17. A frame for an electrical condenser as set forth in claim 12 further characterized in that the frame has bar members located adjacent said rods and extending between and fastened to said end bearing plates, said bar members being

of insulating material to which at least the stator is attached.

18. A frame for an electrical condenser as set forth in claim 12 further characterized in that the frame has bar members located adjacent said rods and extending between and fastened to said end bearing plates, said bar members being of insulating material to which at least the stator is attached, said end bearing plates being slotted to receive said insulating bars and also having notches adjacent said slots, and double flanged collars forcibly positioned in said slots to hold said bars therein.

19. An electrical condenser as set forth in claim 1, further characterized in that a plurality of groups of stator and rotor elements are provided to form a gang condenser, at least two of said rods having additional grooves spaced between said groups of elements, and shield plates 20 tightly fitting in said grooves similarly to said end plates, said rods having further additional annular grooves for receiving stator support elements.

20. For an electrical condenser having stator and rotor groups of plates, a frame including two end bearing plates for the rotor shaft held in fixed spaced relationship by a plurality of metal rods of relatively large diameter disposed at least one on each side of the frame, said rods 30 and end plates having forced interlocking fits made integral by welding, said rods having relatively large lateral bearings at least on the inside portions of the end plates.

21. An electrical condenser as set forth in claim 1, further characterized in that at least two of said rods have longitudinal grooves extending for at least the major portion of the length thereof, members fastened in said grooves and

extending away from the rods, at least one bushing of insulating material carried by said members, said bushing having an eyelet going therethrough and a metallic arm fastened to the eyelet and to a stator element tie bar.

22. An electrical condenser as set forth in claim 1, further characterized in that at least two of said rods have longitudinal grooves extending for at least the major portion of the length thereof, members fastened in said grooves 10 and extending away from the rods, at least one bushing of insulating material carried by said members, said bushing having an eyelet going therethrough, a metallic arm fastened to the eyelet and to a stator element tie bar, further characterized in that a trimmer plate is fastened to said insulator by said eyelet.

23. For an electrical condenser having stator and rotor groups of plates, a frame including two end bearing plates for the rotor shaft held in fixed spaced relationship by a plurality of metal rods disposed at least one on each side of the frame, said rods at their extremities and the end plates having cooperative formations such that these parts may be permanently anchored together, further characterized in that at least two of said rods have longitudinal grooves therein, insulators fastened in said grooves and extending away from the rods, at least one metallic stud carried by each insulator and extending 30 to a point near a stator tie bar and soldered thereto, and a trimmer plate held to said insulator by said stud and extending into capacity relationship with said rod, with means carried by the rod for adjusting the position of the 35 trimmer plate with respect thereto.

STANLEY S. CRAMER.
